UNITED STATES PATENT OFFICE.

RAYMOND DUNCAN, OF NEW YORK, N. Y.

STOP MECHANISM FOR TALKING-MACHINES.

1,346,082.

Specification of Letters Patent.

Patented July 6, 1920.

Application filed April 21, 1915. Serial No. 22,776.

To all whom it may concern:

Be it known that I, RAYMOND DUNCAN, a citizen of the United States, residing at the city of New York, borough of Manhattan, in the county and State of New York, have invented certain new and useful Improvements in Stop Mechanism for Talking-Machines, of which the following is a full, clear, and exact specification.

10 My invention relates to improvements in talking machines, and the same has for its object more particularly to provide a simple, efficient and positive device, whereby the driving mechanism may be arrested 15 when the record has been played.

Further, said invention has for its object to provide a stop for talking machines which is so constructed and arranged that the same may be operated ordinarily as an 20 automatic device when a record has been completely played, or which may be operated manually to stop the driving mechanism when the reproducer is at any point upon the record.

25 Further, said invention has for its object to provide a stop mechanism whereby the driving mechanism will be automatically stopped when the needle or stylus carried by the reproducer reaches the end of 30 the groove.

Further, said invention has for its object to provide an automatic mechanism which is actuated directly by the record to arrest the driving mechanism of the 35 machine when a predetermined point has been reached upon the record.

To the attainment of the aforesaid objects and ends, my invention consists in the novel details of construction, and in the 40 combination, connection and arrangement of parts hereinafter more fully described and then pointed out in the claims.

In the accompanying drawings forming part of this specification wherein like numerals of reference indicate like parts,—

Figure 1 is a side view showing a well-known form of talking machine equipped with a stop mechanism constructed according to, and embodying my said invention; 50 Fig. 2 is an enlarged detail plan view partly broken out to illustrate the stop mechanism;

Fig. 3 is a detail side elevation partly in section;

55 Fig. 4 is a detail perspective view of the

stop mechanism and the parts directly cooperating therewith;

Fig. 5 is an enlarged detail front view of the sound box, and

Fig. 6 is an enlarged detail side view 60 showing the circuit closer operated by the brake lever.

In said drawings 10 designates a talking machine casing which may be of any desired shape or size, and comprises a removable top plate 11 suitably supported within the top of the casing 10. Below said plate or top 11 is secured the usual motor 12 from which extends upwardly through the top plate 11 a shaft 13 upon which is mounted the turn table 14 to receive the record 15. At the forward side of the machine, which is the left hand side, as seen at Fig. 1, is arranged a vertical shaft 16 having its lower end disposed in a socket 17 secured 75 upon the horizontal partition 18, in the casing 10. The upper end of the shaft 16 extends through a collar 19 secured in the top 11^a of the casing, and at the upper end of said shaft 16 is pivotally secured a cam 80 20 provided with an operating handle 21 whereby said shaft and parts carried thereby may be raised or lowered.

22 denotes a horn which is secured at its forward end by clips or brackets 23, 23^a to 85 the shaft 16 adjacent to its upper and lower ends.

The rear end of the horn is reduced in diameter and extends upward and forwardly, and to its extreme upper end is removably secured the reproducing apparatus which comprises a diaphragm case 24 and a floating arm 25. The rear end of the floating arm 25 is pivotally secured to the diaphragm case 24 by a spring 27 and is 90 electrically insulated from the diaphragm case by a block of insulating material 26. The spring 27 permits of a slight vertical movement of the forward or free end of the floating arm. The member on the floating 100 arm which carries the stylus or needle is operatively connected to the diaphragm within the case 24 by a flexible connection 28. At the forward end of the case 24 is secured a loop 29 which loosely embraces the limit 105 pin 30 secured to the free end of the floating arm 25. The said reproducing apparatus comprising the above enumerated parts will hereinafter be designated by the term sound-box.

Upon the base or plate 11 adjacent to the forward end of the apparatus is arranged a brake lever 31 which is pivotally supported upon a pin or screw 32. Said brake lever is provided at its front edge with a forwardly and upwardly extending member 33 having a friction block 34 therein serving as a brake shoe. At its opposite edge said brake lever 31 is provided with a depending projection 35.

36 denotes a locking lever which is pivotally secured to the base 11 by a pin or screw 37 which extends through the rear end of said lever. At its forward end said lever is provided with a laterally offset portion 38 having a forwardly extending curved finger-portion 39. Adjacent to its rear or pivoted end the locking lever 36 is provided with a recess 40 which is adapted to engage with the projection 35 of the brake lever when the said brake lever is forced inwardly to release the friction block 34 from its engagement with the inner surface of the depending flange 14^a of the turn table 14.

25 The rear end of the locking lever 36 is connected by a spring 41 with an inwardly extending arm 31^a on the brake lever 31. The offset portion 38 at the forward end of the locking member serves as an armature to be actuated by a magnet 42 secured upon the top 11^a by a bracket 43.

To one side of the locking lever 36 are secured a pair of contact fingers 44, 45 which are insulated from each other and from the plate 11 by blocks of insulating material 46, 46^a. The forward ends of said contact fingers 44, 45 are normally separated, and are adapted to be brought into engagement with each other to complete the electric current at that point by a wedged-shaped block of insulating material 47 which has its rear end split and secured to the brake lever 31.

48 denotes a dry battery and 49 a conductor extending from one of the poles of said battery to the pivoted rear end of the floating arm 25. 50 denotes a conductor which extends from the opposite pole of the battery, and to the contact member 45. From 50 the contact member 44 extends a conductor 51 which includes the magnet 42, and has its end connected to a contact finger 52, secured upon the horizontal partition 18, which contact finger is adapted to engage with the collar of the clip or projection 23^a secured to the lower end of the shaft 16 and to the horn 22. By lowering the cam 20 at the upper end of the shaft 16 the stylus or needle carried by the floating arm 25 will 60 be brought into engagement with the record 15 upon the turn table 14.

The operation of the apparatus is as follows:—

The free end of the brake lever 31 is first 65 moved inwardly in the direction of the ar-

row a, Fig. 4 whereby the friction block 34 is freed of its engagement with the inner surface of the depending flange 14^a of the turn table 14, and at the same time the projection 35 at the rear edge of said lever 31 70 is caused to engage with the locking lever 36 and force the same slightly to the left, and when said locking lever 36 has reached the limit of its movement to engage with the recess 40 therein whereby said brake 75 lever 31 will be held in its retracted position. The forward end of the locking lever 36 is held normally away from the core of the magnet 42 by the action of the spring 41 secured to the rear ends of said locking 80 and said brake lever. As the brake lever 31 is forced inwardly, as just above stated, the wedged-shaped member 47 carried thereby will be caused to engage the upper surface of the contact finger 44, and force the same 85 downwardly into engagement with the free forward end of the contact spring 45, and thus complete the circuit between the conductors 50 and 51.

Hereupon the sound-box and the horn 22 90 are bodily lowered and the stylus or needle of the sound-box caused to engage with the surface of the record by adjusting to a vertical position the handle 21 secured to the upper end of the vertical shaft 16. As the 95 said shaft 16 and horn 22 carried thereby are bodily lowered the contact finger 52 will be caused to engage with the clip or brackets 23^a at the lower end of the shaft 16, and complete the electric circuit at that point. 100 The circuit will now be completed except for the break which exists between the limit pin 30 and the yoke 29 extending from the underside of the diaphragm case and loosely embracing said pin. When the sound-box 105 has moved inwardly toward the center of the record to the point where the record ends a peculiar lateral jump or movement of the forward end of the floating arm 25 occurs. This lateral movement is in an inwardly direction toward the center of the record, and occurs as the stylus or needle suddenly moves from the end of the record groove to the smooth portion of the record disk. As the floating arm 25 is thus caused 110 to jump or move suddenly the limit pin 30 will be brought into engagement with the loop 29 on the diaphragm case 24 and finally complete the electric circuit. With the completion of the electric circuit the magnet 42 115 instantly becomes energized and attracts the portion 38 of the locking lever 36 thereto, and holds the same until the circuit is again broken. As the forward end of the locking lever 36 is so attracted by the magnet 42 the 120 projection 35 on the brake arm 31 will be released from its engagement with the recess 40 adjacent to the other end of said locking lever 36, and said lever brake 31 caused to spring outwardly under the influence of the 125 130

spring 41, and force the friction block 34 against the inner side of the vertical flange 14^a of the turn table 14, and thereby arrest the further movement of said turn table. 5 As the brake arm is projected outwardly by the action of the spring 41 the wedged-shaped member 47, carried thereby, will also be moved outwardly and in being so moved outwardly cause the contact finger 44 to be 10 released from its engagement with the contact finger 45 and break the electric circuit.

If it is desired to stop the rotation of the turn table 14 at any point between the beginning and end of a record, it merely becomes necessary to force the free end of the locking lever 36 against the magnet 42 whereby the brake lever 31 will be released in the same manner as it is when the magnet 42 is energized. To start the turn table again it merely becomes necessary to force the brake lever 31 inwardly and cause the recess 40 thereof to engage with the projection 35 on the rear side of said brake lever 25 whereupon the parts will be held in position to permit of the free rotation of the turn table.

It will be noted that my invention provides a stop mechanism which operates automatically to arrest the movement of the driving mechanism when, for example, the record has been played, and which may be actuated independently of the automatically operating means to arrest the driving mechanism at any desired point or place on the record.

Having thus described my said invention, what I claim and desire to secure by Letters Patent is:—

40 1. In a machine of the character described, in combination, a rotatable record support, a record thereon, means for operating the support, a sound-box comprising a plurality of parts one of which is movable with respect to the other thereof, and a brake mechanism, certain of said parts of said sound-box being operatively connected to the brake mechanism and being operable by the record for controlling the operation 45 of the brake mechanism to arrest the movement of the record support, substantially as specified.

50 2. In a machine of the character described, in combination, a rotatable record support, a record thereon, means for operating the support, a sound-box comprising a plurality of parts one of which is movable with respect to the other thereof, and a brake mechanism, the relatively movable parts of said sound-box including co-acting members operatively connected to the brake mechanism, certain of said members being operable by the record for controlling the operation of the brake mechanism to arrest

the movement of the record support, substantially as specified. 65

3. In a machine of the character described, in combination, a rotatable record support, a record thereon, means for operating the support, a sound-box comprising a plurality of parts one of which is movable with respect to the other thereof, and an electrically controlled brake mechanism, the relatively movable parts of said sound-box including co-acting members forming a circuit-closer, said circuit-closer being operable by the record for controlling the operation of the brake mechanism to arrest the movement of the record support, substantially as specified. 70 75

4. In a machine of the character described, in combination, a rotatable record support, a record thereon, means for operating the support, a sound-box comprising a plurality of parts one of which is movable with respect to the other thereof, and an electrically controlled brake mechanism, one of the parts of said sound-box comprising a member, and another of the parts of said sound-box comprising a second member embracing said first-named member and constituting therewith a circuit-closer, said circuit-closer being operable by the record for controlling the operation of the brake mechanism to arrest the movement of the record support, substantially as specified. 80 85 90

5. In a machine of the character described, in combination, a rotatable record support, a record thereon, means for operating the support, a sound-box comprising a plurality of parts one of which is movable with respect to the other thereof, and an electrically controlled brake mechanism, one of the parts of said sound-box comprising a pin, and another of the parts of said sound-box comprising a loop embracing said pin and constituting therewith a circuit-closer, said circuit-closer being operable by the record for controlling the operation of the brake mechanism to arrest the movement of the record support, substantially as specified. 100 105 110

6. In a machine of the character described, in combination, a rotatable support, means for operating the same, a brake mechanism, 115 and a sound-box comprising relatively movable co-acting parts operatively connected to the brake mechanism for controlling the operation thereof, substantially as specified.

7. In a machine of the character described, 120 in combination, a rotatable support, means for operating the same, an electrically controlled brake mechanism, and a sound-box comprising relatively movable co-acting parts electrically insulated from one another and constituting a circuit-closer to control the operation of the brake mechanism, substantially as specified. 125

8. In a machine of the character described, in combination, a movable member, means for controlling the movement thereof, and a sound-box comprising relatively movable co-acting parts operatively connected to said controlling means for governing the operation thereof, substantially as specified. 65
9. In a machine of the character described, in combination, a movable member, electrically controlled means for governing the movement thereof, and a sound-box comprising relatively movable co-acting parts electrically insulated from one another and constituting a circuit-closer for governing the operation of said electrically controlled means, substantially as specified. 70
10. In a machine of the character described, in combination, a movable member, electrically controlled means for governing the movement thereof, and a sound-box comprising a plurality of parts one of which is movable with respect to the other thereof, one of said parts constituting one member of a circuit-closer and another of said parts 75
- 20 constituting another member of the circuit-closer, said members being insulated from one another, said circuit-closer governing the operation of said electrically controlled means, substantially as specified. 80
- 25 11. In a machine of the character described, in combination, a movable member, electrically controlled means for governing the movement thereof, and a sound-box comprising a plurality of parts one of which is movable with respect to the other thereof, one of said parts including a member, and another of said parts including a second member electrically insulated from said first member and constituting therewith a circuit- 85
- 30 closer for governing the operation of said electrically controlled means, substantially as specified. 90
- 35 12. In a machine of the character described, in combination, a movable member, electrically controlled means for governing the movement thereof, and a sound-box comprising a plurality of parts one of which is movable with respect to the other and electrically insulated therefrom, said electrically 95
- 40 insulated parts of the sound-box including co-acting members constituting a circuit-closer for governing the operation of said electrically controlled means, substantially as specified. 100
- 45 13. In a machine of the character described, in combination, a movable member, electrically controlled means for governing the movement thereof, and a sound-box comprising a plurality of parts one of which is movable with respect to the other and electrically insulated therefrom, one of said parts including a pin, and another of said parts including a member embracing said pin and constituting therewith a circuit- 105
- 50 closer for governing said electrically controlled means, substantially as specified. 110
- 55 14. In a machine of the character described, in combination, a movable member, electrically controlled means for governing the movement thereof, and a sound-box comprising a diaphragm case and a floating arm, said case and arm including co-acting members insulated from one another and constituting a circuit-closer for governing said electrically controlled means, substantially as specified. 115
- 60 15. In a machine of the character described, in combination, a movable member, electrically controlled means for governing the movement thereof, and a sound-box comprising a diaphragm case and a floating arm electrically insulated from one another, said case and said arm including co-acting members constituting a circuit-closer for governing said electrically controlled means, substantially as specified. 120
- 65 16. In a machine of the character described, the combination of a rotatable record support, a record thereon, a reproducer comprising a stylus, means for shifting said reproducer vertically relatively to said record, with a stop mechanism comprising a pivoted brake lever, means for maintaining said pivoted brake lever normally projected and in engagement with said record support, a projection on said brake lever, a pivoted locking lever having a recess therein adapted to engage with the projection on said brake lever whereby to hold said brake lever in retracted position, an armature on said locking lever, a circuit, a source of electric energy, an electro magnet, a circuit closer arranged partly upon a fixed part of the machine and partly upon the means for vertically shifting said reproducer, a pair of contact members mounted in separated relation adjacent to said brake lever, a member on said brake lever adapted to engage with said contact members and move the same into engagement with each other, said reproducer comprising a pair of contact members normally in engagement and adapted to be separated when the stylus on the reproducer is moved vertically into engagement with said record and said first-named contact members being adapted to be brought into engagement when said brake lever is shifted to its retracted position, said second named contact members being adapted to complete the circuit when the stylus reaches a predetermined point upon the record whereby to energize said electro-magnet to release said locking lever and cause said brake lever to be projected into engagement with said record support, and the member carried thereby to be released from its engagement with the contact members first mentioned, substantially as specified. 125

17. In a device of the class described, the combination, with a record support and a sound box arranged for relative feeding movement, of a record on said support, said sound box being so arranged with respect to said support and the record thereon that as the stylus of the sound box leaves the groove of the record there will be a component of the friction between the stylus and record which will produce a movement of the stylus across the record, and means whereby the movement of the stylus across the record thus produced controls the relative feeding movement of the record support and sound box, substantially as described.

18. In a device of the class described, a movable member, means comprising an electric circuit for controlling the movement thereof, and a sound box having relatively movable parts adapted to effect the closing of said circuit by relative movement thereof to thereby control the operation of said controlling means, the operation of said controlling means effecting the breaking of said circuit.

19. In a device of the class described, a rotatable record support, a brake mechanism therefor, means comprising an electric circuit for controlling said brake mechanism, and a sound box having relatively movable parts and adapted to effect the closing of

said circuit by relative movement thereof to thereby render said brake mechanism operative, the operation of the brake mechanism effecting the breaking of said circuit, substantially as described.

20. In a device of the class described, the combination with a rotatable record support and a member provided with a sound box mounted for relative feeding movement, of a brake mechanism for said support, means comprising an electric circuit for controlling said brake mechanism, said sound box having a part movable relatively to the sound box body and having an extension comprising a contact element, and a contact element fixed to said member, said contact elements being normally electrically disconnected from each other and comprising a circuit closer for said circuit, and said circuit closer being rendered operable by movement of said part relative to the sound box body, substantially as described.

Signed at the city of New York, in the county and State of New York, this 16th day of April, one thousand nine hundred and fifteen.
